UNITED STATES PATENT OFFICE

156,862

SWEATER

Hans Boepple, New York, N. Y.

Application March 1, 1949, Serial No. 1,141

Term of patent 7 years

(Cl. D3—4)

To all whom it may concern:

Be it known that I, Hans Boepple, a citizen of the United States of America, residing in New York city, county of New York, and State of New York, have invented a new, original, and ornamental Design for a Sweater, of which the following is a specification, reference being had to the accompanying drawing, forming part thereof, wherein the figure is a front elevational view of a sweater showing my new design.

The back of the sweater is substantially plain in appearance.

I claim:

The ornamental design for a sweater, substantially as shown and described.

HANS BOEPPLE.
